BLOWER VALVE

Chester J. Scanlan, Bloomington, Ill.

Application April 16, 1937, Serial No. 137,342

1 Claim. (Cl. 137—152)

This invention relates to an improved valve for a blower which is particularly adapted for use in connection with a boiler or furnace of the under-feed type, but it is to be understood that 5 it may be used in connection with the fire-box of any furnace.

Blowers as now constructed consist of a pipe or conduit having one end portion extending into the boiler or furnace under the grates of the fire-10 box and a fan housing at the outer end of the pipe from which air is forced through the pipe and up through a head at the inner end of the pipe for passage through the fire-box. Such blowers have not been found entirely satisfactory, 15 this being particularly true when used with a furnace of the under-feed type as when the fan is automatically shut off sufficient air to create a good combustion will be lacking and coal in the fire-box will coke.

20 Therefore, one object of this invention is to provide a valve for a blower having its conduit or pipe so constructed that, when the fan is shut off, the valve provided intermediate the length of the pipe will be opened and thus allow sufficient 25 air to enter for supporting combustion in the fire-box and causing the coal to burn evenly instead of volatile gases being driven off and coke being formed.

Another object of the invention is to so 30 construct the auxiliary air inlet intermediate the length of the pipe or conduit and so construct and mount the valve for this auxiliary air inlet that, when the blower is not in use, the valve will turn to a vertical position and permit air to enter the conduit, the valve when in this vertical position extending downwardly into the conduit to such an extent that, when the fan is turned on, the blast of air passing through the pipe to the furnace will act upon the valve and move it to a 35 closed position and thus prevent the air from escaping through the auxiliary air inlet instead of passing into the furnace or boiler under the grate and upwardly through the coal in the fire-box.

40 Another object of the invention is to so construct the auxiliary air inlet that movement of the pivoted valve plate in a closing direction may be limited and a tight closure formed when the valve plate is in the closing position.

45 It is another object of the invention to provide means for limiting movement of the valve in the opening direction and also to provide the auxiliary air inlet with a hood which will act as a shield and prevent ashes or other matter from 50 dropping through the inlet into the conduit or

pipe and interfering with proper movement of the valve or free passage of air through the conduit when the blower is in operation.

The invention is illustrated in the accompanying drawings, wherein

5 Figure 1 is a view partially in side elevation and partially in section showing the improved blower in operative relation to a boiler,

Figure 2 is a sectional view taken longitudinally through the air pipe and the auxiliary air inlet 10 of the blower,

Figure 3 is a top plan view of Figure 2,

Figure 4 is a view similar to Figure 2 illustrating a modified construction wherein a hood is provided for the auxiliary air inlet and an adjustable 15 abutment provided to limit opening movement of the valve, and

Figure 5 is a sectional view taken along the line 5—5 of Figure 4.

20 The furnace or boiler 1 is of a conventional construction and is formed with the usual fire-box having a grate 2 at its bottom, the grate being disposed at the top of a pit 4 from which air passes upwardly through the grate and through the pit of coal in the fire-box. A stoker, which is indicated in general by the numeral 5, is provided for supplying coal to the fire-box. This stoker is 25 of the under-feed type and coal is fed from the stoker into the fire-box in the usual manner.

30 In order to supply an adequate draft of air, there has been provided a blower consisting of an air pipe or conduit 6 which may be of any length and diameter desired. One end portion of this conduit or pipe extends into the pit 4 under the grate 2 and terminates in an upwardly extending 35 outlet head 7 through which air passes upwardly and after leaving the discharge head flows upwardly through the grate and through the bed of coal in the fire-box. At its outer end the conduit 6 is connected with a fan housing 8 in which a 40 rotary fan 9 is mounted. A side wall of the fan housing has been shown formed with an air inlet 10, and it will be understood that both side walls may be similarly formed with air inlets so that, when the fan is in operation, air may be drawn 45 into the housing and then forced through the air pipe or conduit 6 to the head 7 at the inner end thereof and upwardly from this head through the fire-box. The fan will be automatically turned on and off when necessary by control means of a conventional construction. While the openings 50 10 in the side walls of the housing 8 permit a certain amount of air to enter the fan housing when the fan is shut off and pass through the conduit or pipe 6, a sufficient quantity of air to support 55

combustion is lacking and as a result volatile gases are driven off, thus leaving the fixed carbon in the form of coke. This coke forms a somewhat solid mass through which the air does not properly penetrate when the fan is again turned on and the coal in the fire-box does not burn properly.

In order to prevent the formation of coke, the conduit or pipe 6 has been provided with an auxiliary air inlet intermediate its length through which sufficient air may enter the conduit when the fan is shut off and thus support combustion which will cause the coal in the fire-box to burn slowly without forming coke. The auxiliary air inlet is in the form of a neck 11 which rises from the air pipe or conduit 6 intermediate the length thereof and is open at its upper end, as shown in Figure 2. Flanges 12 and 13, which may be referred to as a lower flange and an upper flange, extend about marginal portions of the open upper end of the neck 11, and it should be noted that the flanges extend across the opposite ends of the neck with their arms extending along side portions of the neck. The arms of the flange 13 extend toward the arms of the flange 12 but are in a higher plane than the flange 12 and its arms, and they terminate in spaced relation to ends of the arms of the flange 12. Therefore, when the valve 14 is in the vertically disposed or opened position, it may extend vertically between the spaced ends of the arms, as shown in Figure 1 and as indicated by dotted lines in Figure 2. This valve is in the form of a plate which may be sheet metal and intermediate its length is formed with a transversely extending bearing 15 through which a pivot rod 16 passes with ends of the rod projecting from opposite sides of the plate and rotatably engaged through side walls of the neck 11. The plate or valve will thus be pivotally mounted for swinging movement from the opened position, indicated by dotted lines in Figure 2, to the closed position shown in full lines in this figure, and attention is called to the fact that the valve is so balanced that, when the fan is shut off, the valve will swing to the opened position and air may enter through the upper end of the neck and pass through the air pipe or conduit 6 and up through the head 7 at the inner end thereof. Therefore, sufficient air will be supplied for supporting combustion and the coal in the fire-box will burn slowly instead of the volatile gases being driven off and coke being formed. When the fan is turned on, the blast of air passing through the air pipe will strike the lower end of the valve plate and swing this plate upwardly to the closed position where it will make contact with the flanges 12 and 13 and close the upper end of the auxiliary air inlet neck. This will cause all of the air from the fan to pass through the air pipe to the head 7 and upwardly from this head through the coal in the fire-box. It will thus be seen that the auxiliary air inlet will be closed when the fan is in operation and pre-

vent air from escaping through this air inlet neck, whereas when the fan is shut off, the valve will move to the open position and air will be permitted to enter the air pipe.

In Figures 4 and 5, there has been illustrated a modified construction. In this embodiment of the invention, the auxiliary air inlet or neck 17 of the air pipe or conduit 18 is provided with internal flanges 19 and 20 instead of having upper marginal portions of its walls bent inwardly to form the flanges. These flanges serve the same purpose as the flanges 12 and 13, and between spaced ends of their arms a valve plate 21 is pivotally mounted by a pivot pin 22 extending transversely of the valve plate through a bearing 23. A screw 24 serving as an abutment to limit movement of the valve in the opening direction is threaded through an opening formed in one wall of the neck and a nut 25 is provided upon this screw so that, when the screw has been properly adjusted to permit opening of the valve plate to the desired position, the nut may be tightened and the screw secured in the adjusted position. Side walls of the neck 17 extend upwardly above end walls thereof and are united to each other to form a hood 26 which serves very effectively to prevent ashes and other foreign matter from accidentally dropping through the neck into the air pipe and creating an obstruction which would be liable to interfere with free movement of the valve into or out of an opened position and also interfere with movement of air through the air pipe. End portions of the hood are extended beyond end walls of the neck 17, as shown at 27, to effectively guard the neck and prevent material from dropping into the neck. While the hood will very effectively prevent ashes and other material from accidentally dropping into the neck, it will not prevent the desired flow of air through the neck and into the air pipe when the fan is shut off.

Having thus described the invention, what is claimed as new is:

In a device of the character described, an air pipe, a neck extending upwardly from the air pipe about an opening formed therein and constituting an auxiliary air inlet, a valve plate pivotally mounted in said neck for tilting movement about a horizontal axis from a vertical opened position to a horizontal closed position across the neck, upper and lower flanges mounted horizontally in the neck against walls thereof and disposed at opposite sides of the axis for engaging opposite faces of the valve plate and limiting closing movement of the valve, an open-ended hood for the upper end of said neck constituting means for preventing foreign matter entering the neck, and a screw carried by the neck and constituting an adjustable abutment for engagement by the valve plate to limit movement of the valve in an opening direction.
